United States Patent Office.

FRANCIS F. BIBBER, OF SOUTH BOSTON, MASSACHUSETTS.

Design No. 4,666, dated February 21, 1871.

DESIGN FOR A RAILROAD-STATION INDICATOR.

The Schedule referred to in these Letters Patent and making part of the same.

To all whom it may concern:

Be it known that I, FRANCIS F. BIBBER, of Boston, and State of Massachusetts, have invented and produced a new and original Design for Railroad-station Indicators, of which the following is a specification.

The nature of my design is fully represented in the accompanying drawing, to which reference is made, in which—

A represents the front of the indicator.

a, an opening in the front, through which the names of the stations can be read as the cloth or other ma-

terial on which the names are given is transferred from roller b to b', or the reverse.

B is the back of the indicator, which reflects the light and illuminates the names of the stations as they are passed between the rollers b and b'.

Claim.

I claim as my invention—

The design for a railroad-station indicator, as shown.

Witnesses: FRANCIS F. BIBBER.
